Application February 24, 1958, Serial No. 49,776

Term of patent 14 years

(Cl. D45—4)

FIG. 1

FIG. 2

FIG. 5

FIG. 4

FIG. 3

Fig. 1 is a top plan view of an expandable chain for a bracelet or similar article, showing my new design;

Fig. 2 is a top plan view thereof in a partially expanded position;

Fig. 3 is a side elevational view thereof;

Fig. 4 is an enlarged side elevational view of an end link thereof; and

Fig. 5 is an enlarged top plan view of an end link thereof.

The square crosshatching shown on the end links represents the color black.

The dominant features of my design reside in the portions shown in full lines.

I claim:

The ornamental design for an expandable chain for a bracelet or similar article, substantially as shown and described.
